US0D1074644S

(12) **United States Design Patent** (10) **Patent No.:** **US D1,074,644 S**
(45) **Date of Patent:** **** May 13, 2025**

(54) **SHORT VIDEO REMOTE CONTROLLER**

(71) Applicant: **Danni Wu**, Dongguan (CN)

(72) Inventor: **Danni Wu**, Dongguan (CN)

(**) Term: **15 Years**

(21) Appl. No.: **29/922,460**

(22) Filed: **Dec. 22, 2023**

(30) **Foreign Application Priority Data**

Jun. 26, 2023 (CN) 202330393227.7

(51) **LOC (15) Cl.** **14-03**

(52) **U.S. Cl.**

USPC **D14/218**

(58) **Field of Classification Search**

USPC ..... D14/218, 454, 499, 496, 400, 401, 432, D14/455, 456, 511, 217, 238.1, 399; D13/168, 171, 167, 173-184; D21/333 CPC G08C 17/02; G08C 19/00; G08C 19/12; G08C 19/28; G08C 23/04; G08C 2201/91; G06F 3/0238; G06F 3/01; G06F 3/0308; G06F 3/033; G06F 3/0338; G06F 3/038; G06F 3/03543; H01H 9/02; H01H 9/0214; H01H 9/0228; H01H 9/025; H01H 9/0235; H01H 9/0242

(57) **CLAIM**

The ornamental design for a short video remote controller as shown and described.

DESCRIPTION

FIG. 1 is a perspective view of a short video remote controller showing the new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
